CLAIM

The ornamental design for an extendable tie rack, as shown.

DESCRIPTION

FIG. 1 is a perspective view of an extendable tie rack showing my new design;

FIG. 2 is an enlarged front elevational view thereof;

FIG. 3 is an enlarged rear elevational view thereof;

FIG. 4 is a bottom plan view thereof;

FIG. 5 is a side elevational view taken from the left of FIG. 1;

FIG. 6 is an enlarged fragmentary perspective view thereof.
